[57] CLAIM

The ornamental design for a chair, as shown and described.

DESCRIPTION

FIG. 1 is a left-front perspective view of the chair showing our new design;

FIG. 2 is a left-front perspective view of a second embodiment of the chair showing our new design, wherein the sole difference is the configuration of the armrest members;

FIG. 3 is a front view of the chair shown in FIG. 1;

FIG. 4 is a rear view of the chair shown in FIG. 1;

FIG. 5 is a left side view of the chair shown in FIG. 1;

FIG. 6 is a right side view of the chair shown in FIG. 1;

FIG. 7 is a top view of the chair shown in FIG. 1;

FIG. 8 is a bottom view of the chair shown in FIG. 1;

FIG. 9 is a left-front perspective view of a third embodiment of the chair shown in FIG. 1, wherein the sole difference is the height of the backrest; and,

FIG. 10 is a left-front perspective view of a fourth embodiment of the chair shown in FIG. 1, wherein the sole differences are the height of the backrest and the configuration of the armrest members.

The fragmented cross-hatching represents fabric, which would be continuous throughout the implied areas.
